United States Patent Office

Des. 189,630
Patented Jan. 17, 1961

189,630

OPTICAL SIGHT UNIT

Carl F. Brown, Jr., Huntingdon, Pa., assignor to Waid Industries, Inc., Huntingdon, Pa., a corporation of Pennsylvania

Filed June 15, 1960, Ser. No. 60,979

Term of patent 14 years

(Cl. D57—1)

I claim:

The ornamental design for an optical sight unit, as shown.
